ABSTRACT

A pilot for a large capacity gas burner which uses a fixed metering orifice instead of an adjustable needle valve to produce a constant and reliable flame for igniting a relatively large capacity gas burner.

PILOT FOR GAS BURNER

This invention relates to pilots for large heat capacity gas burners.

The automatic and continuous processing of agricultural and industrial products at times requires a large supply of air heated to a predetermined temperature. The source of the heated air may be a gas burner the temperature of the flame of which is considerably higher than the temperature desired in the heated air, and hence the products of combustion of the burner are mixed with a stream of air supplied by a fan or blower. The capacity of the burner is selected to handle peak loads and hence, for average loads, an on-off operation of the burner and blower is effected. This requires that the burner be periodically lit and extinguished throughout the processing operation, and this, in turn, requires the use of a reliable pilot to ignite the burner unfailingly every time heat is called for. In prior pilot designs, the gas for the pilot was supplied from a tube or pipe through an adjustable needle valve. It was felt that each installation of the pilot required a different quantity of gas to insure continuous operation of the pilot, and hence the needle valve was provided to permit regulating the quantity of gas supplied to the pilot flame. However, the operation of the pilot was found to be erratic and no adjustment of the valve would cure this defect.

An object of this invention is to provide a pilot for a gas burner wherein the pilot will function uniformly under variable conditions of operation of the gas burner and of the air supplied thereto.

As a more specific object this invention has within its purview the provision of a pilot for a gas burner which is simpler to construct and maintain and hence less expensive than pilots heretofore designed.

It is also an object of this invention to provide a pilot for a gas burner wherein the pilot requires no adjustment as to the quantity of gas burned by said pilot, the quantity being determined by a fixed metering orifice through which the said gas is fed to the pilot.

These and other objects of the invention will become apparent from the following detailed description of a preferred embodiment thereof when taken together with the accompanying drawings in which:

FIG. 1 is a fragmentary section through the prior art pilot valve with an adjustable needle valve;

FIG. 2 is a section through a pilot burner and associated igniter and other components of this invention, the section being taken along line 2—2 of FIG. 3;

FIG. 3 is an end elevation of the pilot burner of FIG. 2; and

FIG. 4 is a schematic diagram of a typical installation of a pilot of this invention.

For purposes of illustration, this invention will be described with reference to a pilot burner used with automated grain dryers which use propane gas as a fuel and a powerful fan for (1) supplying air to the burning gas, (2) mixing the hot products of combustion with air to reduce to a safe level the temperature of the heated air contacting the grain, and (3) creating a pressure differential across the grain column in the dryer to promote passage of the hot air through the grain. The pilot burner is ignited once for each continuous run of the dryer, but during such run, the fan and main burner may be periodically turned on and off as dictated by an appropriate control in the dryer to prevent overheating of the grain. After the grain has been heated and dried, it must be cooled, while in the dryer by using only the fan, the burner being shut off during this cooling cycle. The pilot burner must therefore remain lit under both full fan and still fan conditions, and under full fan with and without burner operation.

The pilot burner is located in a housing in which are also located a thermocouple which senses whether the pilot has been ignited, and an electric igniter for igniting the pilot. Also enclosed in the same housing is a gas jet which is turned on with the main burner and assists in igniting the latter.

The environment in which the pilot valve of this invention is designed to operate is shown in FIG. 4. The dryer 47 may be of the type disclosed in U.S. Pat. No. 3,056,214, granted to A.

Andersen, Jr. on Oct. 2, 1962. Said dryer has a cylindrical burner section 48 in which is located a high-capacity gas burner 49 and a fan 50 driven by a motor 51. Fan 50 supplies outside to the dryer after mixing with the hot products of combustion of burner 49. The pilot assembly 52 is disposed adjacent burner 49 with its axis crosswise to the airstream from fan 50.

Referring now to the drawings for a detailed description of the pilot valve, there will be described first the prior art needle valve shown in FIG. 1. In that Figure, the pilot valve as adapted for use with grain dryers is shown at 10 and is comprised of a "T"-shaped fitting 11 having an internal thread 12 at one end and an internal thread 13 at its other end. Said other end is closed by a plug 14 which is threaded to cooperate with internal threads 13, said plug having a flange 15 by which it is located against the end of fitting 11.

Plug 14 has a central axial orifice 16 at the end of a conical seat 17 which cooperates with the conical point 18 of a needle valve 19. Said valve 19 has an enlarged threaded end 20 which cooperates with internal threads 12 for adjusting the position of conical end 18 relative to seat 17 whereby to adjust the flow of gas to the orifice 16. The inlet to the fitting 11 is at 21 and said inlet is connected to a suitable supply of propane gas (not shown).

Air for combustion is supplied to the gas issuing from orifice 16 in a mixing chamber 22 formed by a tube 45 threaded over exterior threads 23 on fitting 10, said chamber 22 having air inlet openings 24 adjacent plug 14, and outlet openings in the closed end 46 consisting of a central large opening 25 and a series of smaller angularly disposed openings 26 surrounding the central opening 25, the burning gas and air mixture being disposed outside of tube 45.

When installed in a grain dryer, for example, the pilot assembly of FIG. 1 is disposed with the axis of the pilot transverse to the general direction of movement of air from the fan 50 through the burner 49. The fan, and the burner ignited by the pilot assembly of FIG. 1, are intermittently operated so that the pilot is exposed to full fan conditions at one time and at another, to still fan conditions. Furthermore, during the cooling cycle of the grain dryer, the fan and the pilot may be on, but the burner will be off, so that the pilot must operate under three extreme conditions.

It has been found that the operation of the pilot of FIG. 1 is erratic in that it will go out at unexpected times, and when the pilot ceases to function, the main burner cannot be relit. The sensing of a lack of flame in the pilot by a thermocouple, to be described hereinafter in connection with FIG. 3, causes a shutdown of the burner as a safety measure, and this, in turn, causes a shutdown of the entire drying mechanism. Diligent investigation of the pilot of FIG. 1 failed to disclose any reason for the erratic behavior of the pilot.

I have found that the erratic behavior of the pilot can be corrected by eliminating pilot valve 19. A pilot assembly so made is disclosed in FIGS. 2 and 3. In these Figures, the inlet for the gas for the pilot is comprised of a straight tube 27 which is externally threaded at both ends to receive at one end a fitting 28 by which the tube is connected to an appropriate pipe or tube leading to the source of propane gas, and to receive at its other end the mixing chamber 22. A plug 29 is threaded into the end of tube 27, said plug having an orifice 30 centrally located therein, the length of the orifice being determined by a counterbore 31 adjacent orifice 30. Although counterbore 31 is tapered at its end adjacent orifice 30, the taper is not used as a seat for a valve as in the FIG. 1 design.

Tube 27 is secured to a casting 32 through which it extends, said casting supporting a tubular housing 33, the right-hand end of which is of reduced conical form 34, leaving a relatively large opening 35 for the pilot flame.

The pilot tube 27 is located eccentrically of the housing 33, the central position within the housing being occupied by a second gas inlet tube 36 which is connected to the main gas burner (not shown) so that whenever the main gas burner is turned on, tube 36 will be filled with gas. Said tube 36 is closed

at its right-hand end by a cap 37 threaded thereon and in which is formed a relatively large orifice 38 through which gas from the interior of tube 36 flows into the opening 35 in housing 33. It is contemplated that gas issuing from orifice 38 will be ignited by the flame from the openings 25 and 26 of the pilot mixing chamber 22 and will assist in igniting the main burner.

The pilot is ignited by a pair of electrodes 39, 40 which are of known construction and are retained in appropriate fittings 41 threadedly received in casting 32. A thermocouple 42 extends inwardly adjacent the openings 25 and 26 in a known manner to sense whether the pilot is lit. Said thermocouple is connected to the controls of the dryer (not shown) to shut the dryer down in the event the pilot is not lit. Air for the combustion of the pilot gas is supplied through openings 43 in housing 33 adjacent openings 24 in mixing chamber 22, said openings 43 in housing 33 being shielded by one or more scoops 44 which promote the entry of air from the fan of the dryer into the openings 43.

The fixed orifice design of pilot shown in FIGS. 2 and 3 has been found to provide a steady pilot flame under all operating conditions of the dryer including full fan, still fan, and full fan with and without full burner. Although it is not known why the absence of the needle valve should cure the erratic behavior of the prior art pilot, it is surmised that the needle valve in some

way changed its position relative to orifice 16 and at times obstructed the flow of gas through the orifice, so that by eliminating the needle valve, the obstruction was also eliminated. It is understood, of course, that the size of the orifice 30 in FIG. 2 is calculated to provide the proper flow of gas into mixing chamber 22.

We claim:

- 10 1. A pilot for a gas burner comprising a tube having an inlet opening for combustible gas, an outlet opening for the tube comprising a fixed orifice in direct constant communication with the interior of the tube, and an air-and-gas mixing chamber adjacent the orifice, a housing for the pilot having an opening for the flame produced by the pilot, an intermittently operable gas burner in the housing adapted to be ignited by the pilot, and a gas burner of greater capacity than the first said gas burner and disposed to emit gas at right angles to the direction of the first said gas burner, said gas burner of greater capacity being substantially ignited by the flame from the first said gas burner.
- 15 2. A pilot as described in claim 1, said housing being substantially cylindrical around said pilot and frustoconical around the flame produced by said pilot, and means creating a variable stream of air moving across said housing transversely of the axis of said pilot.
